(57) **CLAIM**

The ornamental design for a floor covering panel, as shown and described.

DESCRIPTION

FIG. 1 is a top perspective view of a floor covering panel; FIG. 2 is a bottom perspective view of the floor covering panel shown in FIG. 1;

FIG. 3 is top plan view of the floor covering panel shown in FIG. 1;

FIG. 4 is a bottom plan view of the floor covering panel shown in FIG. 1;

FIG. 5 is a front elevation view of the floor covering panel shown in FIG. 1;

FIG. 6 is a rear elevation view of the floor covering panel shown in FIG. 1;

FIG. 7 is a left-side elevation view of the floor covering panel shown in FIG. 1; and,

FIG. 8 is a right-side elevation view of the floor covering panel shown in FIG. 1.

The drawings contain symbolic break lines. The break lines as well as the portions between the break lines form no part of the claimed design.
